SASH OPERATING DEVICE

Edward L. Ackerman, Detroit, Mich., assignor to
 Ackerman-Blaesser-Fezzey, Inc., Detroit, Mich.,
 a corporation of Michigan

Application June 29, 1929. Serial No. 374,743

1 Claim. (Cl. 268—126)

This invention relates to sash operating devices, the object being to provide a simple and inexpensive device for the sliding of a sash in its frame and may be used with various types of windows and is particularly adapted for use with windows of a closed automobile body.

The purpose of the invention is to provide a structure that is adapted for use with different weights of sash and may be adjusted either to 10 counterbalance the same or to such condition that the regulator will automatically raise the sash in its frame.

A further feature of the invention resides in the provision of parts whereby application of pressure to the sash in the raising or lowering operation is maintained substantially centrally between the side rails thereof in any of the adjusted positions of the sash in its frame.

These and other objects and novel features of 20 the invention are hereinafter more fully described and claimed, and the preferred form of a sash operating mechanism embodying my invention is shown in the accompanying drawing in which—

25 Fig. 1 is an elevation of my improved sash operating mechanism.

Fig. 2 is an edge view thereof taken from the left side of Fig. 1.

Fig. 3 is a perspective of a device utilizable in 30 adjusting the spring tension.

No attempt is here made to illustrate the sash or the frame in which it is slideable such structures with which the device is adapted for use being commonly well known and illustrated in my application for patent for Window regulator, Serial No. 362,556, filed May 13, 1929.

In its preferred form the device consists of a plate 1 adapted to be mounted upon a cross member of the window recess and revolvably supported in this plate is a shaft 2 extending to opposite sides of the plate. The end shown in Fig. 1 is provided with a slot to receive the inner end of a spiral coiled spring 3, the outer end of which is secured in the slotted end of a pin 4 secured to 40 the adjusting element 5. This element 5 is provided with a toothed periphery 6 and adjacent the periphery is a series of apertures 7 circularly arranged. A screw 8 is provided and insertable through one of the apertures 7 into a threaded aperture in the plate 1 to hold the member 5 in its adjusted position. The plate is provided with an aperture 9 directly beneath the threaded aperture for the screw 8 to receive an adjusting tool shown in Fig. 3 which is provided with an end 50 portion 10 for introduction into the aperture and

a toothed portion 11 for engaging the teeth 6 of the member 5. As will be readily understood to either increase or decrease the tension of the spring, the adjusting member shown in Fig. 3 has its end portion 10 inserted in the aperture 9 with the teeth 11 meshing with the teeth of the member 6. The screw is then removed and the adjusting member turned in one direction or the other as the case may be to secure the desired tension of the spring 3 and the screw 8 then reinserted to hold the member 5 in its adjusted position.

On the opposite end of the shaft 2 is secured a plate 12 having a toothed periphery 13 adapted to engage a gear of the control element illustrated generally at 14. This control element may be of a type indicated in detail in my said pending application Serial No. 362,556, or in U. S. Letters Patent to myself and A. J. Zwierzina, No. 1,657,561 issued January 31, 1928. The control element illustrated in the said pending application Serial

No. 362,556 is of the type to be utilized with this structure when the spring element is intended to be used under a tension sufficient of itself to raise the sash in its frame while the control element shown in the said U. S. Patent No. 1,657,561 is used when the tension of the spring is intended to practically counterbalance the weight of the sash and through operation of which the sash may be manually raised or lowered and it is not material to the levers, gear segment and springs,

the tension of the springs may be made to practically counterbalance the sash when the device is used with a control element as shown in the said U. S. Patent No. 1,657,561 and in the control shown in the application Serial No. 362,556 the spring 3 is adjusted in tension sufficient to actually move the sash to closed position when permitted through association therewith of a control device adapted for such purpose.

This arrangement of the structure is well adapted for use in a restricted space as usual in automobile bodies inasmuch as the parts including the gears and gear segments, plate, levers etc., may be formed of stamped sheet metal and the space occupied from front to back thereof thus reduced to a minimum.

By the described arrangement of the parts I am also able to secure a device practically free from rattle through looseness of parts. In providing the extension 15 and slot 16 therein through which the shaft 17 extends and with the companion ends of the levers 18 and 19 connected with the shaft 17 on opposite sides of the extension, an arrangement is secured preventing lateral movement of these lever ends. By this

means the opposite end of the regulator arm is also prevented from lateral displacement or strain tending to produce lateral displacement relative to the sash and thus prevents a cramping of the parts.

The device is operable by means of a crank attached to the control element 14 through rotation of which the plate 12 is turned on the axis of the shaft 2 and depending upon the direction 10 in which the plate 12 is turned, the sash engaging arm 19 will be raised or lowered. In order that the sash engaging roller 20 at the free end of the arm 19 may be maintained approximately on a center line between the opposite sides of a 15 sash, the lever 19 is pivotally supported to the extension 15 of the plate 1 it being adapted to ride in the arcuate slot 16 formed in the said extension and caused to move therein by reason of the pivotally fixed relationship between the plate 12 and the arm 19. In the lowermost position of the 20 sash engaging end 20 of the arm 19, and consequently of the sash connected therewith, the shaft 17 will occupy the end 22 of the slot 16 while in the uppermost position of the said parts 25 the shaft 17 will occupy the end 23 of the slot. The shaft 17 is also pivoted in the upper end of the lever 18 which is fulcrumed in the fixed plate 90. The spring 24 has its inner end fixed to the shaft 17 and its outer end secured to a pin 25 fixed to the lever 18 and, as the lever 18 is pivoted on the shaft 17, the tension of the spring 24 is applied through the lever 19 to, in part, support the sash.

These levers 18 and 19 lie on opposite sides of 35 the extension 15 of the plate 1 and in close association therewith and lateral movement is practically prevented. The tension of the spring 3 is also applied to support the sash by means of 40 the gear segment 12 which is pivotally attached to the regulator arm 19. It will also be seen that while the pivot point of the plate 12 on the arm 19 must move through a circular path by turning the element 12, the sash engaging end 20 of the arm is maintained approximately on the vertical center line of the sash at any of its possible points of movement through operation of

the regulator by reason of the pivotally supported end of the arm 19 being capable of movement relative to the extension plate 15. By use of the spring 3 and means for adjusting its tension the weight of the sash may be counter-balanced and, if desired, the tension may be increased to a point sufficient to automatically raise the sash in its frame.

From the foregoing description it is evident that the device is simple and comparatively inexpensive in construction and that the various objects of the invention are attained by the structure or the equivalent thereof shown in the accompanying drawing.

Having thus briefly described my invention, 90 what I claim and desire to secure by Letters Patent of the United States is—

In sash operating mechanism, a base plate having a vertical and horizontal portion, a shaft rotatably supported in the lower end of the base plate at a right angle to the plane thereof, the horizontal portion of the plate extending at a right angle to the axis of the shaft, a gear segment supported on one end of the shaft, a spirally coiled spring on the opposite end thereof tending to rotate the shaft in one direction, means for adjusting the tension of the spring, a lever- 95 age means with which the gear segment is connected comprising a regulator arm one end of which is in operative engagement with a sash, a lever having one end in pivotal relation with the opposite end of the regulator arm by means of a shaft extending between the aforesaid ends of the regulator arm and the lever, the said ends of the arm and lever being on opposite sides of the horizontal portion of the plate, said portion of the plate having an arcuate slot for the said shaft between the regulator arm and the lever, the other end of the lever being pivotally supported 100 at a fixed point distant from the plate, a spring tending to operate the regulator arm and lever, and a control device through operation of which the position of the gear segment about its axis may be determined to thereby relatively position the regulator arm and sash engaged thereby.

EDWARD L. ACKERMAN.
